WASHING MACHINE

Harry J. Criner, Davenport, Iowa, assignor of one-half to A. G. Bush, Davenport, Iowa

Application August 20, 1948, Serial No. 45,406

8 Claims. (Cl. 68—23)

1

My invention relates to washing machines and the objects of my invention are to provide a washing machine and a process by which the clothes are washed in a revolving spinner and during the washing process are carried outwardly to the side walls of the spinner and upwardly along the side-walls into contact with a curved semi-dome-shaped annular cover whereby they are returned to the central part of the spinner; to provide means by which clothes may be washed in a revolving spinner enclosed in a tub or housing and the water withdrawn from the clothes by centrifugal force without emptying the tub; to provide means for circulating the water from a tub to a circular spinner mounted therein and from the spinner back to the tub, with additional means for controlling or shutting off such circulation. Other objects will appear from the specification.

I accomplish these objects by the means illustrated in the accompanying drawings, in which;

Figure 1 is a sectional elevation of my machine on the line 1—1 of Figure 2;

Figure 2 is a top or plan view of my machine with the covers broken away to show the interior;

Figure 3 is a sectional detail showing an alternate form of shut-off lever and valve;

Figure 4 is a fractional plan view of the spinner with the alternate form of shut-off lever and valve;

Figure 5 is a detail elevation of the shut-off lever; and

Figure 6 is a detail showing the arrangement of the alternate form of shut-off valve;

Figure 7 is a plan view of a spinner 12 with corrugations 13 formed in the sides of the spinner in place of the vanes 13;

Figure 8 is a sectional elevation on the line 8—8 of Figure 7;

Figure 9 is a sectional detail on the line 9—9 of Figure 8.

Similar numerals refer to similar parts throughout the several views.

My invention comprises a circular housing 1 the bottom of which is reenforced by an annular flange 3 supported by the castors 6. The top of the housing 1 is formed with a bead 5 rolled thereon and provided with a cover 7 closely fitting within the bead. A handle 8 is united to the middle of the cover 7.

Approximately midway of the housing 1 a circular plate 2 is united to the housing on the interior thereof by soldering, by welding or other suitable means, which forms the bottom of the tub portion of my machine.

2

An outlet tube 21 is mounted in the bottom plate 2 by which the water may be withdrawn from the tub when desired.

A crossbar 26 is mounted in the housing below the bottom plate 2 and may be secured by rivets 27 or other suitable means. A tube or column 25 is rigidly united to the crossbar 26 at the center of the housing and has a shaft 24 revolvably mounted therein in bearings 28 and 29. Diagonal braces 25.1 may be united to the column 25 and the crossbar 26 to strengthen same.

Mounted upon the top of the shaft 24 by a pressfit is a boss 23 with an enlarged circular head 22 and with a screw-threaded portion 16 formed integral therewith. A unit 11 is mounted upon the screw-threaded plug 16 and arranged to hold upon the head 22 the bottom of a circular spinner 12 having side walls which extend upwardly from the bottom plate and are inclined outwardly from the bottom plate.

Upon the lower end of the shaft 24, a pulley 30 is rigidly mounted to be driven by a belt which in turn is driven by a belt pulley 32 mounted upon the end of the shaft of the motor 33.

The housing of the motor 33 is mounted upon a pivot-shaft mounted in brackets or lugs 35 and 36 welded or otherwise suitably united to the housing with a set screw 34.1 to secure the shaft in adjusted position whereby the belt 31 may be tightened to take up slack or loosened to be removed from the pulleys.

The bottom and the side walls of the spinner are united by an arcuate portion and the size and contour of such arcuate portion may be varied to meet the requirements of various cases. This arcuate section performs an important function in promoting the upward movement of both water and clothes as the centrifugal force carries them to the side wall of the spinner and thence up to the annular cover where the water is returned to the tub and the clothes are returned to the middle of the spinner for further washing action.

When the spinner is arranged to travel at the very high speed of 400 R. P. M. or more, such curved portion may be relatively small, but may be made larger so as to facilitate the outward and upward movement of the water and the clothes when acted upon by centrifugal force. Likewise, the angle of inclination of the side walls of the spinner 12 may be varied as desired.

Wings or vanes 13 may be united to the side walls of the spinner 12 and extend upwardly inclining to the rear. The width and inclination of these vanes may be varied as desired of different classes of work.

In the bottom of the spinner 12 I provide a port 18 through which the water may pass from the tub into the spinner. A slide valve 19 may be mounted in a casing 20 attached to the bottom of the spinner 12 and arranged to close the port 18 when in one position and to leave it open when withdrawn.

A valve rod 21 is revolvably mounted in bosses 14 and 15 united to the side wall of the spinner 12 and has an arm 21.1 at the lower end with its end turned down to engage a suitable opening in the slide valve 19. The upper end of the rod 21 is provided with a handle 21.2 by which the rod 21 may be rotated sufficiently to cause the arm 21.1 to actuate the slide 19 in either direction.

In the form shown in Figure 3 the head 22 is formed with a circular recess in the top thereof in which an annular valve plate 19.1 is mounted surrounding the plug 16. The head 22 in this case is provided with bores 22.1 arranged to register with bores 18.1 formed in the bottom of the spinner when in one position and to close off the bores 18.1 when in alternate position.

When this rotary form of valve is used, a narrow rod 19.2 may be used in place of the slide valve 19 and the inner end of it turned down and pivotally attached to the rotary valve 19.1.

A semi-dome-shaped annular cover is mounted directly over the upper edge of the spinner and may be held in place by brackets 11 riveted to the cover, and brackets 4 united to the housing 1 by rivets 4.2.

Dowel pins 38 may be united to the brackets 11 and with their lower ends extending into suitable bores formed in brackets 8 to hold the cover 9 in place.

The central portion of the cover 9 is cut away and flanged downwardly at 10 so as to prevent splashing of water and also aid in returning the clothes to the center of the spinner after they are forced upward by the centrifugal action of the spinner and water therein.

The cover 9 is spaced approximately one-eighth of an inch or less above the upper edges of the spinner 12 so as to leave an opening 9.1 through which the water may be driven by centrifugal force as the spinner revolves.

In the operation of this form of my machine the water line is designed to stand at the height shown by the dotted line A in both the spinner and the tub when at rest, but when the spinner is revolved at high speed, the centrifugal force will carry the water over the upper edge of the spinner and out into the tub, and will carry the clothes up into the cover 9 which will deflect them toward the middle of the spinner. At the same time water will flow through the bore 18 up into the spinner and the constant circulation will be kept up while the spinner is revolving.

If desired, the cover 9 may be formed integral with the side walls of the spinner as shown in Figure 3, with an opening 10.1 formed in the top of the cover 9 through which the clothes may be placed in the spinner, and in that case, the cover will revolve with the spinner.

When so constructed, ports 41 are formed around the spinner just below the junction of the spinner and the cover and these ports may be opened or closed by an annular band 39 having corresponding ports 41 formed therein. The annular band 39 is mounted upon an annular support 41.1 riveted to the side wall of the spinner below the line of the ports 41. A handle 39.1 may be united to the annular band 39 to aid in moving 75

it so as to bring the ports 41 into or out of register with the ports 40.

In this form of apparatus, as the spinner revolves, the water will pass out through the ports 41 from the spinner into the tub when the ports 40 and 41 are in register and the clothes will pass up into contact with the cover and back to the middle of the spinner. When the ports are out of register, the water and the clothes will travel upward along the side walls of the spinner 12 until they reach the cover 9 at which point they will be deflected inwardly and caused to drop into the central portion of the spinner.

The washing action of this machine is carried on not only by the movement of the water through the clothes, but also by the rubbing action upon the clothes of the vanes 13, the side walls of the spinner and the cover 9.

In both of the forms shown, the clothes may be dried by centrifugal action by closing the bores 18 or 18.1, the space between the spinner and the side wall of the tub being so proportioned that it will be sufficient to contain all of the water from the spinner if previously filled to the desired water level as shown.

It should be noticed that with my machine the rinsing water may be put in the spinner and the clothes rinsed at the same time that the wash water is being drawn out of the tub through the outlet 2.1 or if desired, the clothes may be dried while the wash water remains in the tub ready to be used to wash a second batch of clothes.

As an alternative to the vanes 13, inclined corrugations 13.1 may be pressed in the side walls of the spinner 12 as shown in Figures 7 and 8 and horizontal corrugations 9.1 may be formed in the cover 9. Such corrugations will cause a rubbing action upon the clothes coming in contact therewith and thus improve the washing action of the machine and process described.

It is obvious that various changes may be made in the size, shape, proportions and arrangements of the various parts without departing from the spirit of my invention and I do not limit my claims to the precise forms shown in the drawings.

I claim:

1. In a washing machine, a housing with a lower supporting portion and an upper tub portion integral therewith, a transverse support rigidly mounted in the supporting portion, a central bearing carried by said support, a driving shaft journaled in said bearing and means for rotating the driving shaft, a tub-like spinner with its bottom united to the upper end of the driving shaft and having an upwardly extending peripheral side wall inclining outwardly from its bottom to the top, a semi-dome-shaped annular cover positioned over said spinner with the outer edge of the cover corresponding in size and shape to the upper edge of the spinner and with the inner edge of the cover projecting inwardly and upwardly to a circle of about one-third of the greatest diameter of the spinner whereby the movement of the spinner and the water therein will tend to deflect the upwardly moving clothes inwardly and downwardly toward the center when brought into contact therewith by centrifugal force and by the upward movement of the water along the side wall of the spinner, ports in the bottom of the spinner and manually controllable valves arranged to admit or to shut off the flow of water through the ports from the tub into the spinner.
2. In a washing machine as described in claim

1, said cover being spaced a short distance above the rim of the spinner whereby water may pass over the rim of the spinner and to the tub without carrying the clothes with it.

3. In a washing machine as described in claim 1, and upwardly and rearwardly inclined vanes united to the side wall of the spinner on the inside thereof arranged to augment the upward movement of water along the side wall of the spinner when revolved.

4. A washing machine as described in claim 1, with inwardly extending rearwardly and upwardly inclined corrugations formed in the side wall of the spinner arranged to produce rubbing action upon the clothes being washed therein and to augment the upward movement of the water and the clothes along the side wall of the spinner when revolved.

5. A washing machine as described in claim 1, said ports comprising one or more openings in the bottom of the spinner and the valves including a slide having corresponding openings arranged to register with the openings in the bottom of the spinner when in open position and to close said openings when in closed position.

6. A washing machine as described in claim 5, and a manually operable shaft journaled upon the side of the spinner having a handle at its upper end and an arm at its lower end pivotally united to the valve slide.

7. In a washing machine, a housing with a lower supporting portion and an upper tub portion integral therewith, a transverse support rigidly mounted in the lower portion, a central bearing block carried by the support, a driving shaft journaled in said block, a tub-like spinner with its bottom united to the upper end of the driving shaft and having an upwardly extending peripheral side wall inclining outwardly from its bottom, a semi-dome-shaped annular cover over said spinner with the outer edge of the cover corresponding in size and shape to the upper edge of the spinner and with the inner edge of the cover projecting inwardly and upwardly to a circle of about one-third of the greatest diameter of the spinner whereby the movement of the spinner and the water therein will tend to deflect the upwardly moving clothes inwardly and downwardly when brought into contact therewith by centrifugal force and the movement of the water developed by such spinner, said cover being spaced a short distance not exceeding one-eighth of an inch above the rim of the spinner whereby water may pass over the rim of the spinner to the tub, an arcuate inclined portion uniting the side wall to the

bottom of the spinner arranged to promote upward movement of the water in the spinner along the side wall when the spinner is revolved, upwardly and rearwardly inclined means united to the side wall of the spinner arranged to augment the upward movement of the water along the side wall of the spinner when revolved, and ports and manually operable valves at the bottom of the spinner arranged to admit or shut off the flow of water from the tub into the spinner.

8. In a washing machine, a housing with a lower supporting portion and an upper tub portion integral therewith, a central bearing block rigidly mounted in the lower portion, a driving shaft journaled in said block, a tub-like spinner with its bottom united to the upper end of the driving shaft and having an upwardly extending side wall inclining outwardly from its bottom, a semi-dome-shaped annular cover rigidly united to the upper tub over said spinner with the outer edge of the cover corresponding in size and shape to the upper edge of the spinner, with the inner edge of the cover projecting inwardly and upwardly to a circle of about one-third of the greatest diameter of the spinner, and means to revolve the spinner whereby the movement of the water will tend to carry the clothes upwardly to the cover and the cover will tend to deflect them inwardly and downwardly toward the center of the spinner, said cover being spaced a short distance above the rim of the spinner whereby water may pass over the rim of the spinner to the tub.
